UNITED STATES PATENT OFFICE.

JOHN R. OISHEI, OF BUFFALO, AND ERWIN C. HORTON, OF HAMBURG, NEW YORK, ASSIGNEES, BY DIRECT AND MESNE ASSIGNMENTS, TO TRICO PRODUCTS CORPORATION, OF BUFFALO, NEW YORK.

MOTOR.

Application filed May 3, 1923. Serial No. 636,398.

This invention relates to motors and more particularly to valve operating mechanism for motors.

In motors of the fluid pressure type, and in particular motors operated by suction from the intake manifold of an automobile engine, which suction varies and is not always present in any substantially large degree, it has been found necessary to provide valve operating or valve changing mechanism which may be operated by a very small expenditure of energy and which will be quick and accurate in operation.

In motors of the type illustrated in the drawings herewith, which motors have been connected to the intake manifolds of automobile engines to operate windshield wipers or other devices, and embodying, generally, a fluid pressure chamber having a vane or swinging operating member working therein and which is adapted to be swung by reason of pressures on the sides of the piston, there have been provided valves for automatically changing the direction of movement of the piston by connecting first one side of the vane with the source of suction, and at the same time permitting atmospheric air to enter to the other side of the vane, whereupon, by reason of the difference in pressures the vane is swung; the valves are then reversed and suction is placed upon the other side of the vane and atmospheric air admitted to the reverse side. In order to prevent the equalizing of pressure upon both sides of the vane, which would stop the operation of the motor, and to compensate for wear and to insure a quick and accurate seating or closing of the valves, it is desirable that the valves be controlled by some resilient or yielding means and further, that the movement of the valve or valves from one position to another be made promptly and accurately at the end of the piston stroke. Heretofore, with these requirements in mind, valve actuating means have been provided embodying a spring-controlled valve-actuating member or snap-over device which when moved toward the end of the vane stroke, is intended to throw or snap the valves to their next position. Generally these devices have relied upon the shifting of an actuating spring first to one side and then to the opposite side of the pivotal point of the valve actuating kicker to obtain this snap action. It has been found in practice

that if the spring loses its elasticity or if for any reason the valves or kicker stick or are difficult to move, reversal of the valves is not accomplished as contemplated. Further, it has been found that positive, unyielding valve-actuating members are undesirable for the reason that they will not adjust themselves to compensate for inaccuracies caused by wear of the valves or incidental to manufacture or assembling and are liable to permit the pressures on opposite sides of the piston to equalize and stop the motor.

The objects of the present invention are to provide valve-actuating devices which operate with a quick or snap action to promptly reverse the valves at the proper time, which yieldingly hold the valves in proper positions and at the same time insure a positive movement of the valves to the desired positions; also to provide a valve-operating device of simple form and which is relatively inexpensive to manufacture and assemble, consisting of few parts, and which will quickly and positively perform its functions. Further objects are to provide improvements in valves and valve-actuating devices for motors in the other respects hereinafter set forth and claimed.

In the accompanying drawings:

Fig. 1 is a sectional elevation of a motor embodying the present invention.

Fig. 2 is a sectional elevation thereof showing the valves and valve-actuating means in a different position from that shown in Fig. 1.

Fig. 3 is a section on line 3—3, Fig. 1.

Fig. 4 is a section on line 4—4, Fig. 2, on an enlarged scale.

Fig. 5 is a sectional elevation of a portion of the motor, illustrating the valve-operating means in different positions.

Fig. 6 is a section on line 6—6, Fig. 3, but on an enlarged scale.

Fig. 7 is a section on line 7—7, Fig. 3, but on an enlarged scale.

Fig. 8 is a section on line 8—8, Fig. 3, but on an enlarged scale.

In the drawings, A generally designates the motor having a chamber B in which is mounted the vane C on a shaft D. The motor is provided with suitable ports for the admission of the operating fluid. In the type of motor disclosed, E designates a suction line which is connected to a suitable

source of suction which is in communication with a passage F. The passage F is in communication with passages G and H which in turn communicate with ports at opposite sides of the chamber. I and K designate ports at the opposite sides of the chamber which, in the case of the type of motor disclosed in the drawings, alternately place the chamber on the opposite sides of the vane 10 under a suction influence or supply atmospheric air thereto. These parts may be in any suitable position and may be controlled by any suitable valve or valves. In the form of motor shown, this is accomplished, for 15 example, by means of a valve L illustrated in Fig. 4, the valve L shown being chosen merely for illustrative purposes. In the position shown in Fig. 4, the valve L is closing the suction passage to the side of the chamber which it feeds and atmospheric air is being admitted to that side of the chamber past the seat at the lower portion of the valve and through the port.

The present invention includes means for 25 automatically operating the valves to reverse the swing of the vane. For this purpose, the valve or valves are provided with a suitable operating means. In the embodiment shown, an operating member 10 is provided which 30 has a pair of arms 11 and 12 in engagement with the respective valves. The operating member 10 is pivoted so that when one of the arms is in a raised position, the other will be depressed so that the suction passage 35 will be open to one side of the vane and closed to the other. Upon lowering of the first raised arm, the other arm will be raised and a reverse operation ensue. In the embodiment shown, the member 10 is pivoted 40 to the motor casing and is provided with a suitable spring or other resilient means which is adapted when moved from one side to the other of the pivotal point of the member 10 to automatically move the member 10 45 upon its pivot and actuate the valves.

In order to actuate the valve-operating mechanism, a suitable part or parts preferably actuated from the piston shaft are provided for causing movement of the member 50 10. In the present embodiment, a spring-shifting device 13 is provided for such purpose. The spring is attached at one end to this shifting device, the other end of the spring being secured to the member 10, and 55 as the spring-shifting device is moved from one side to the other of the pivotal axis of the member 10, the member 10 is automatically snapped or turned toward the side to which the spring is moved, independently of 60 further movement of the vane shaft. Any suitable means may be provided for moving the shifting member from the vane shaft or other moving part of the motor. In the motor illustrated, the vane shaft is provided 65 with a pair of lugs 14 which are adapted to

engage the spring-shifting device and to shift the portion of that device to which the spring is attached first to one side and then to the other side of the pivotal axis of the member 10. In the embodiment shown, the 70 spring shifting device is provided with an end 15 whereby it is pivotally supported, and 16 designates a sleeve or bushing extending around the vane shaft and on which said shaft moves. The sleeve or bushing 16 75 is preferably held stationary on the casing and the end 15 of the spring-shifting device bears on the sleeve or bushing so that there is no tendency of the spring-shifting device to move with the shaft until it is engaged 80 by the lugs 14 on the shaft. As shown, this stationary mounting of the sleeve or bushing may be effected by providing the casing with a lug 17 which takes into a notch 18 in the sleeve or bushing 16 and secures the 85 sleeve or bushing against rotation with the piston shaft. In order to secure an accurate and certain shifting of the valves, the spring-shifting device is provided with parts 90 adapted to positively shift the valve-operating member 10. These parts are preferably so positioned that in normal operation when the spring and valves are working properly these positively operating parts will follow the valve-actuating member 10 and if the 95 valves stick or for any other reason the spring does not function to shift the valve-operating member 10, these positive operating parts will force the member 10 to its proper position, thereby positively moving 100 the valves. As illustrated, these parts may comprise a pair of legs 19 and 20 on the spring-shifting device which extend adjacent to a part of the member 10, and which are adapted to positively move the member 10 105 from one side to the other in case the shifting of the end of the spring does not achieve the required results. The legs or positive actuating members being carried by the spring-shifting device and not in rigid 110 connection with the vane shaft, insure a positive and firm action or movement of the valves, but by reason of the fact that as soon as the valves are seated the piston reverses and the lugs 14 move out of engagement with the spring-shifting device, the 115 valves are yieldingly held in position by the spring.

The spring-shifting device 13 being supported from a pivot spaced a distance from 120 the pivot of the valve-actuating means and being engaged by the lugs 14 a short distance below its pivotal point, and the spring being attached to the spring-shifting device a distance below that point, results in an 125 adequate shifting of the spring with only a very small movement of the portion of the spring-shifting device engaged by the lugs. The result is that the spring-shifting device and the lugs may be so formed and posi- 130

tioned that the lugs will not engage the spring-shifting device until practically at the end of the vane swing; therefore, the vane works on the valve-shifting mechanism during only a small part of its movement. This results in a more rapid and effective movement of the vane under lower pressures during the major portion of the stroke and as the valve-shifting mechanism is not engaged until just at the end of the vane stroke, the swinging momentum of the vane under low pressure is sufficient to insure actuation of the valves with the expenditure of a very slight amount of energy. By reason of the fact that the spring-shifting device is suspended from a pivot other than the pivot of the valve-operating means, the valve-operating means need not be permanently mounted on the casing, but may be removable. As shown in the embodiment disclosed, the motor is provided with pintles or lugs 21 and 22 and the valve-operating means provided with recessed portions 23 and 24, into which these pintles fit, the valve-shifting member being held in engagement with the pintles by means of the spring 13. This facilitates manufacture and assembly of the device as the pintle 21 may be readily cast or otherwise formed on the motor casing and a plate 25 bolted or otherwise attached to the casing, which plate carries the pintle 22. In assembling, the valve-operating means may be readily slipped into place with its recessed portions engaging the pintles, the spring-shifting device slung from the shaft or other support, and the spring 13 attached at one end to the spring-shifting device and at the other end to the valve-operating means. This assembly, of course, facilitates replacement or repair of any of the parts.

We claim as our invention:

1. In a motor, a swinging vane, a valve movable into different positions to control the admission of operating fluid to said vane, a member having resilient means operated from said vane for resiliently snapping said valve to said positions when said vane has swung through predetermined angles, and means operated from said vane for positively moving said valve to said positions.
2. In a motor having a swinging vane and a valve movable to different operating positions for controlling the admission of operating fluid to said vane, a member having resilient means movable to cause said valve to assume different operating positions, means operated by said vane for operating said resilient member, and a part operated by said vane for positively moving said valve to said different positions.
3. In a motor having a swinging vane and valve movable to different operating positions for controlling the admission of op-
- erating fluid to said vane, a member having resilient means movable to cause said valve to assume different operating positions, a shifting member adapted to be operated by said vane and having a part engaging said resilient member to shift said resilient member to actuate said valve, and parts movable simultaneously with said first-named part to insure positive operation of said valve in case said resilient member does not actuate said valve.
4. In a motor having a swinging vane and vane shaft and valves for controlling the admission of operating fluid for swinging said vane, valve-actuating and reversing mechanism comprising valve-operating means adapted to move the valves simultaneously from one operating position to another, resilient means engaging said valve-operating means, a shifting device detachably suspended about the axis of said vane shaft and having a part engaging an end of said resilient means to shift said resilient means to automatically snap said valve operating means to predetermined operating positions, said resilient means holding said device operative and against unauthorized displacement, and a part of said vane shaft for swinging said shifting device about the axis of said vane shaft to cause said resilient means to operate said valve-operating means.
5. In a motor having a swinging vane provided with a rock shaft and a valve for controlling the admission of operating fluid thereto, valve-operating means adapted to move said valve to different operating positions, and a shifting device positively moved by said rock shaft, a part establishing resilient engagement between said shifting device and said valve-operating means to automatically spring said valve to position, and a part on said shifting device for positively engaging said valve-operating means to positively move and follow through said valve actuator and then positively hold the latter in its new position.
6. In a motor having a swinging vane provided with a rock shaft, valves for controlling the admission of operating fluid thereto, a bearing on the case of said motor a distance from said rock shaft, valve-operating means releasably engaging said bearing for pivotal movement thereon and interlockingly engaged with said valves to be assisted thereby against lateral displacement, a shifting device pivotally mounted on the axis of said rock shaft, and resilient means connecting said valve-operating means and said shifting device and tending to hold said valve-operating means in engagement with said bearing, and means for moving said shifting device.
7. In a motor having a swinging vane provided with a rock shaft and valves for controlling the admission of operating fluid

- thereto, a bearing on the case of said motor a distance from said rock shaft, valve-operating means releasably engaging said bearing for pivotal movement thereon, a shifting device pivotally connected to said motor adjacent the axis of said rock shaft and operated by said rock shaft, resilient means connecting said valve-operating means and said shifting device and tending to hold said valve-operating means in engagement with said bearing and movable by said shifting device so as to extend at one side or the other of said bearing to automatically shift said valve-operating means, and parts on said shifting device extended beyond said bearing for engaging said valve-operating means to positively move said means.
8. In a fluid pressure motor having a rock shaft, valve mechanism for controlling the operative admission of fluid pressure to the motor for operating the same, comprising a rockable valve operator, a shifting device pivotally suspended on the shaft, a spring connected at one end to the valve operator and at its opposite end to the shifting device and adapted to have its latter end moved under tension by the shifting device to opposite sides of the pivot of said valve operator, means acting to hold the shifting device against accidental displacement and operable by the shaft to engage and positively swing the shifting device to effect such shifting of the spring, and means operable by the shifting device for positively moving the valve operator and thereby shifting the first end of the spring to the opposite sides of the pivot of said valve operator.
9. In a fluid pressure motor having a rock shaft, valve mechanism for controlling the operative admission of fluid pressure to the
- motor for operating the same, comprising a valve operator pivotally mounted at a distance from said shaft and having a part extending away therefrom, a shifting device pivotally suspended on the shaft and extending therefrom toward the valve operator, a spring connected at one end to said part of the valve operator and at its opposite end to the shifting device and adapted to be moved by the latter to opposite sides of the pivotal mounting of the valve operator, and a lug member fixed on the shaft for engaging and swinging said shifting device and having a part overhanging the latter to prevent accidental displacement thereof.
10. In a fluid pressure motor having a rock shaft, valve mechanism for controlling the operative admission of fluid pressure to the motor for operating the same, comprising a valve operator pivoted to assume different operating positions, a shifting device pivoted on the shaft, a spring connected at one end to said valve operator and at its opposite end to the shifting device and adapted to be moved by the latter to opposite sides of the pivotal mounting of the valve operator, said shifting device having spaced legs extending on opposite sides of both the spring and said part of the valve operator, said legs adapted alternately to engage said valve operator part to swing and follow through the valve operator and hold the latter in its respective operating positions, and means operable by and during movement of the shaft for moving the shifting device and following through the movement of the latter to positively hold the legs respectively against the valve operator.
